(57) **CLAIM**

The ornamental design for a combined mailbox, brace and post, as shown and described.

DESCRIPTION

FIG. 1 is a left-side perspective view of a combined mailbox, brace and post showing my new design;
FIG. 2 is a right-side perspective view thereof;
FIG. 3 is a left-side elevation view thereof;
FIG. 4 is a front elevation view thereof; and,
FIG. 5 is a rear elevation view thereof.
All surfaces not shown form no part of the claimed design.

1 Claim, 5 Drawing Sheets
